UNITED STATES PATENT OFFICE.

CHARLES OSEAN, OF WOODCLIFF, NEW JERSEY, ASSIGNOR TO NATIONAL CARBON COMPANY, INC., A CORPORATION OF NEW YORK.

FLASH LIGHT.

Application filed March 24, 1922. Serial No. 546,380.

This invention relates to flashlights and particularly to an improved end cap and spare incandescent lamp holder therefor.

It is advantageous to have a spare lamp readily available to replace an inoperative lamp of a flashlight, and it is most convenient to carry this spare lamp along with the flashlight, desirably within a compartment in the end or bottom cap of the flashlight casing. Accordingly one object of this invention is to provide an improved bottom end cap for flashlight casings which has a spare lamp holder combined therewith in a manner that will not unduly increase the size of the casing. A further object of the invention is to provide a combined end cap and spare lamp holder which is especially adapted for use in conjunction with focusing flashlights.

In general, the foregoing objects are obtained by securing into the tubular body of a threaded end cap of the usual type, a rigid conductive shell that provides a spare lamp compartment within the cap adapted to engage the bottom end of a flashlight battery to support the latter and form a part of the circuit including said battery. In a flashlight of the focusing type, the rigid lamp holder shell may also serve as an abutment to adjust the battery longitudinally to change the position of the operative incandescent lamp with respect to the reflector.

The above and other objects and the novel features of the invention will be apparent from the following description taken in connection with the drawings in which Fig. 1 is a longitudinal sectional view of a flashlight embodying the present invention, parts being shown in elevation. Figures 2 and 3 are respectively a longitudinal sectional view and an end view of the end cap and lamp holder shown in Fig. 1. Figures 4, 5, 6, 7, 8, and 9 are views of other types of combined end cap and lamp holder devices embodying this invention.

Referring to Figures 1, 2 and 3 of the drawing, a flashlight casing C of metal or fibre has a flaring end F that surrounds a reflector R and a glass or lens L. A miniature incandescent lamp A is mounted in the axis of the reflector so that the reflector and lamp are relatively movable with respect to each other along the axis of the reflector to vary the spread of the rays from the lamp.

In the present instance the lamp is so mounted that it may be movable by the axial adjustment of the battery B in the casing C. The lamp A may be supported for such movement by suitable means, the one illustrated being disclosed in the application of Lee J. Voorhees, Serial No. 466,639, filed May 4, 1921 which has matured into Patent 1,668,881 May 8, 1928. Briefly this arrangement comprises a lamp holder or socket 10 slidable in a central aperture in the reflector, a helical spring 11 tending to retain the holder with the lamp A at the inner limit of their adjustment and to maintain the holder always in contact with the central carbon contact of the battery. When the battery is moved against the pressure of the spring, the holder and the lamp move therewith along the axis of the reflector, changing the position of the lamp filament with respect to the focus of the reflector and varying the spread of the rays from the lamp.

The improved means for adjusting the battery B and the lamp A in circuit with it comprises a combined end cap and spare bulb holder that is adjustably and detachably coupled to the bottom end of the casing C. The end cap desirably contains a relatively rigid receptacle to carry the spare part and to engage the bottom end of the battery, said receptacle being a conducting element constituting an electrical connection between the battery B and the cap. The battery is in circuit with a switch S which controls the circuit that includes the lamp A in a well known manner.

The particular form of combined end cap and spare lamp holder shown in Figures 1, 2 and 3 consists of a cap K having a cylindrical body closed at one end 15 and open 95 at the opposite end adjacent to which it is provided with screw threads 16 whereby it may be coupled to and adjusted axially along the threaded portion 17 of the tubular casing C. The spare part receptacle or bulb holder is disposed within the cap K and comprises a substantially tubular shell D of somewhat smaller diameter than the cap, the rear end of the shell D being provided with projections 18 which extend into an interior groove 19 in the cap K and secure the shell D rigidly in place. The shell D provides a compartment or receptacle to hold one or more spare lamps which may be loosely placed therein but are, more desirably,

rigidly mounted so they will not rattle and break. A suitable means for engaging and holding the spare parts or lamps comprises curved spring fingers 20 projecting into the shell D. These fingers are formed integral with a plate 21 that has portions extending under the projections 18 and is clamped against the inside of the wall 15 by the shell D. The end of the shell D adjacent the open end of the cap is open as at 22 to permit the insertion and removal of the lamps between the fingers 20 and the inner wall of the shell D. The outer edge of the shell D is inturned slightly as at 23 to provide a substantially flat, plane or equivalent surface for bearing against and contacting with the bottom of the battery B.

In operation, as the cap K is turned to screw it onto the casing C, the flange 23 will engage the battery B and push it and the socket 10 against the pressure of the spring 11 to change the position of the filament of the lamp A with respect to the focus of the reflector B. By turning the cap in the reverse direction the compressed spring is free to expand and move the lamp A and its socket to the limit of their movement in the return direction. The threaded cap will retain the lamp A in any position of adjustment, and may be readily detached from the casing C to obtain access to the spare lamp holder, the lamps being in sight when the cap is removed.

A desirable type of end cap and spare lamp holder has been shown and described but it will be understood that the invention may be embodied in other types of spare lamp holders and flashlights without departing from the spirit of the invention or sacrificing any of its advantages. For example, Figures 4 and 5 illustrate an end cap and bulb holder in which the shell D' that forms the spare lamp holder is held in the groove 191 of the cap K' by projections 181, as in the form shown in Figures 1, 2 and 3. The outer end of the shell D' is closed by a cover G that may be detachably fitted thereon in any suitable way, and, as illustrated, may be provided with screw threads 28 to cooperate with screw threads 29 on the shell D'. The cover G may be knurled as at 30 to facilitate its removal and the spare part or lamps within the shell D' may be held in place by any suitable means, as by paper or cotton packing 31.

In Figures 6 and 7 another form of spare lamp holder is illustrated in which a shell D² is held in place in the groove 192 in the cap K² by projections 182. A narrow hinged cover member G' latches on the shell and is arranged to cover only a part of the open end of the shell D² to enable the user to see the spare lamps therein and yet hold them in place.

The end cap and spare lamp holder illus-

trated in Figures 8 and 9 consists of a shell D³ which is held in place in the interior groove 193 of the cap K³ and has a central rigid projection 35 upon the outer end thereof that is adapted to engage the bottom end of the battery B. The outer wall 36 of the shell D³ is punched out as shown to provide pairs of intersecting openings 37 and 38 of different diameters, the larger opening 37 to admit the bulb of the lamp into the shell and the smaller opening 38 being of a size to receive and engage the base of the lamp to securely hold it.

It will be understood that in all of the combined end cap and spare bulb holders illustrated the shell within the end cap that provides the compartment for holding one or more spare bulbs performs the additional and important functions in the usual flashlight of providing a base of considerable area bearing against the bottom of the battery B to hold it in contact with the lamp socket and of providing conducting means between the bottom of the battery B and the end cap. In a focusing flashlight, as illustrated, the spare lamp receptacle also acts as a follower rigid with the end cap to move the battery and adjust the lamp with respect to the focus of the reflector.

I claim:

1. The combination of a cap closed at one end and threaded adjacent its other end whereby it may be adjustably and detachably coupled to a flashlight casing, and spare lamp carrying means secured in said cap comprising a conductive tubular shell spaced from the tubular wall of said cap and lamp holding means inside said shell.

2. The combination of a cap closed at one end, open at the opposite end and threaded adjacent such open end whereby it may be detachably coupled to a flashlight casing, and a spare lamp carrying shell having one end secured to said cap and the other end arranged for the insertion and removal of a spare lamp, such shell being also arranged to bear against the bottom end of a cell in said casing.

3. The combination of a tubular body threaded adjacent one end whereby it may be coupled to a flashlight casing, a spare lamp holder shell secured in said body, and a cover within said body for said shell.

4. The combination of a cap threaded adjacent one end whereby it may be detachably coupled to a flashlight casing, spare lamp carrying means comprising a shell secured in said cap, and a cover for said shell adapted to engage against the bottom end of a cell in said casing.

5. The combination of a cap threaded adjacent one end whereby it may be detachably coupled to a flashlight casing, said cap having an interior groove, and a spare lamp holder comprising a shell secured in said

groove and shorter than the cap, and a cover for said shell constructed and adapted to bear against the bottom of a cell in said casing.

5 6. A flashlight comprising the combination of an incandescent lamp, a reflector, means whereby said lamp and said reflector are relatively adjustable, a battery in circuit with said lamp and movable to effect a relative adjustment of said lamp and said reflector, a casing for said battery, receptacle means bearing against the bottom end of said battery, and an end cap adjustably coupled to said casing and arranged so that 10 its adjustment causes movement of said receptacle means and said battery.

7. A flashlight comprising the combination of an incandescent lamp, a supporting member therefor, a reflecting member, means 15 rendering said members relatively adjustable including a spring tending to retain them in one extreme position of adjustment, a bat-

tery bearing against one of said members and movable axially therewith in both directions, a casing for said battery, a spare part holder bearing against the bottom of said battery, and an end cap carrying said spare part holder and adjustably coupled to said casing.

8. A flashlight comprising the combination of an incandescent lamp, a reflector, a socket for said lamp adjustably mounted in the axis of said reflector, a spring tending to retain said socket in one extreme position of its adjustment relatively to said reflector, a battery adjustable axially with said socket in both directions, a casing, a conductive spare lamp container engaging the bottom of said battery, and an end cap carrying said spare lamp container and adjustably and removably coupled to said casing.

In testimony whereof, I affix my signature.

CHARLES OSEAN.
